**MEANS AND TECHNIQUES FOR MAKING
ELECTRICAL CONNECTIONS**

Lee M. Griswold, Pasadena, Calif., assignor to Digital Sensors Inc., Los Angeles, Calif., a corporation of California

Filed Apr. 21, 1964, Ser. No. 361,490
9 Claims. (Cl. 219—36)

The present invention relates generally to a method and apparatus for making an electrical connection to a conductor embedded in insulating material and is particularly useful for making electrical connections to a flexible ribbon-type cable in which the body of the ribbon is a plastic insulating material and parallel-spaced, thin ribbon-type conductors are spaced and embedded in the plastic ribbon.

The present application is a continuation-in-part of my copending application Serial No. 176,729, filed March 1, 1962, now abandoned.

Briefly, the arrangement as described herein involves the use of a pair of heated electrodes between which the parts to be electrically connected are disposed. One of such parts is a ribbon-type cable as described above and the other part may, for example, be a similar ribbon-type cable or an insulated or an uninsulated wire or terminal pin. The parts to be electrically connected are squeezed together by the heated electrodes, forcing themselves through the insulation by heat softening and flowing or crowding of the insulation until those metal parts that are ultimately to be electrically connected are in physical contact, after which a welding current is passed between the electrodes and parts to spot-weld or resistance-weld such parts together in a permanent electrical connection. The welding current may be initiated either in accordance with a signal developed when the parts are in metallic contact or when the pressure between the electrodes exceeds a predetermined amount.

It is therefore an object of the present invention to provide new means and techniques for accomplishing the above-described operations and results.

A specific object of the present invention is to provide improved means and techniques for making electrical connections to a flexible ribbon-type cable.

Another specific object of the present invention is to provide improved means and techniques for selectively connecting different conductors of different ribbon-type cables together in a permanent electrical connection without appreciably increasing the overall thickness of the two ribbon-type cables.

Another specific object of the present invention is to provide improved means and techniques for making terminal connections to conductors of a flexible ribbon-type cable.

The features of the present invention which are believed to be novel are set forth with particularity in the appended claims. This invention itself, both as to its organization and manner of operation, together with further objects and advantages thereof, may be best understood by reference to the following description taken in connection with the accompanying drawings in which:

FIG. 1 is a top plan view of two ribbon-type cables which are electrically interconnected in accordance with features of the present invention.

FIG. 2 illustrates the apparatus for producing the connection illustrated in FIG. 1.

FIG. 3 is an enlarged view of a portion of the two ribbon-type cables illustrated in FIG. 1.

FIG. 4 is a view similar to FIG. 3 and exemplifies other types of connections between the two ribbon-type cables.

2

FIG. 5 is a sectional view generally as indicated by the line 5—5 in FIG. 4 prior, however, to commencement of the operation performed by the apparatus shown in FIG. 2.

5 FIG. 6 is a view like FIG. 5 and serves to illustrate the completion of one electrical connection and also the position of the electrodes at the time the welding current is passed therethrough for bonding adjacent conductors in adjacent cables.

FIG. 7 is a perspective view illustrating one step in the process of connecting a connector pin or tap or wire or solder pin to a conductor of a ribbon-type cable.

FIG. 8 is a perspective view for purposes of illustrating another method and the resulting terminal construction.

15 The ribbon-type cables referred to herein are commercially available and, as illustrated in FIG. 1, comprise an assembly of spaced thin ribbon-type copper conductors 10 embedded in a thin ribbon-shaped plastic 11 which may be of polyethylene, a polyester or Mylar. Such 20 insulating material may either be a thermoplastic resin or a thermosetting resin. A like ribbon-type cable, to which electrical connections are made, is illustrated as having conductors 20 and insulating material 21, and the latter ribbon-type cable, as shown in FIG. 1, has four 25 connector pins or solder pins connected thereto using the method illustrated in FIG. 7.

30 FIG. 1 illustrates two electrical connections between the two cables, such connections being illustrated at 30 and 31, and such connections are made as now described 35 in connection with FIG. 2.

35 In FIG. 2, there is provided heated spot-welding type electrodes 40 and 41 between which the ribbon-type cables are disposed. The electrodes 40 and 41 are in the form of pointed rods and are each bolted in heat-conductive relationship to a relatively heavy massive metal bar 42 and 43, respectively, such bars being in heat-conductive relationship with corresponding electric heaters 44 and 45 supplied with heating current through the heater wires illustrated. The lower electrode 41 is preferably maintained stationary and serves in the nature of an anvil, while the upper electrode 40 is movable for compressing the adjacent tape sections together in the manner illustrated in FIGS. 5 and 6. FIG. 5 illustrates the initial position of the electrodes 40 and 41, and FIG. 6 illustrates their final position wherein the electrodes 40 and 41 are in electrical contact with corresponding conductors in corresponding cables.

40 It will be seen that FIGS. 4, 5 and 6 have reference to a different arrangement of connections between the conductors of the four-conductor cable 20, 21 and the seven-conductor cable 10, 11 for purposes of demonstrating the versatility of the invention and in such case there are four electrical connections 32, 33, 34 and 35. Two of the conductors 10, as illustrated, are interrupted as, for 45 example, by piercing or shearing portions out of the tape 10, 11. The interrupted ends of one of the conductors 10, as illustrated in FIG. 4, are connected at 32 and 33 to different conductors 20; and likewise, the interrupted ends of a different conductor 10 are connected at 34 and 35 to other conductors 20.

50 During the application of pressure between the electrodes 40 and 41, heat is transferred from such electrodes 40 and 41 to the insulation 11 and 21 to soften and crowd such insulation out of the path of the advancing electrodes 40 and 41 and also to soften and crowd the insulation between conductors 10 and 20 until ultimately there is a metal-to-metal contact between electrode 40 and conductor 10, and also a metal-to-metal contact between electrode 41 and conductor 20, and also a metal-to-metal contact between the conductors 10 and 20. When this condition is achieved, a welding current is 55 caused to flow through this series electrical circuit de-

scribed from source 50 which has one of its terminals connected to the electrode 40 and the other one of its terminals connected to the electrode 41. Such welding current is caused to flow automatically when the above-mentioned condition is achieved, using either one of two techniques now described. As illustrated in FIG. 2, there is provided a pressure-sensitive switch 51 having its actuating element in the path of movement of the movable electrode structure 40, 42, 44 so as to be actuated thereby when the force or pressure applied to such moving electrode structure exceeds a predetermined amount, in which case the switch 51 is closed to fully energize the source 50 and to produce the above-described flow of welding current between electrodes 40 and 41. For purposes of illustration, such switch 51 is illustrated as being actuatable by the extension 42A of plate 42. A source of welding current so controlled may be, for example, of the type made under the name Weldmatic by Unitek Corporation of Monrovia, California.

An alternative arrangement for initiating the flow of welding current involves an electric sensing circuit which is closed when the condition illustrated in FIG. 6 is established, whereupon such sensing circuit is operative to produce full energization of the welding current source 50 and resulting flow of welding current between electrodes 40 and 41.

The technique is also applicable to welding connector pins or soldering pins 30 to the ends of the four-conductor cable 20, 21 as illustrated in FIG. 7. In this case, the connector pin 30 is a bare wire and the movable electrode 40 is then provided with a conforming arcuate grooved portion 40A at its end for snugly engaging the wire 30A when and as it is being heated and being pressed through the insulation 21 and into metallic engagement with the underlying conductor 20. Simultaneously, the lower heated electrode 41 also softens the adjacent insulation and crowds itself into metallic contact with the underside of the conductor 20. The flow of welding current is then initiated as described above.

Referring to FIG. 8, it illustrates another method of achieving electrical contact and mechanical connection of a connector pin or soldering pin 130 to each of the ends of a multiconductor cable 120, 121. In this case, the connector pin 130 is a bare wire which is initially placed in physical contact with a cable conductor 120 by physically inserting an end of the pin in a sandwiched condition between such conductor and that portion of the insulating material overlying the same. To facilitate such insertion, one end of the pin may be pointed for easy insertion and/or a narrow small cutting tool such as, for example, an end portion of a razor blade may be used to separate the plastic insulating material from the conductor. In any case, the insertion of the pin results in the overlying insulating plastic material being crowded away from the conductor and forming a conforming pocket for the pin which is then self-maintained in such pocket by the stressed or stretched insulating material. While the end connection thus formed by the protruding pin may be used, preferably a better mechanical and electrical connection between the pin and cable conductor is provided using techniques described above and the electrodes 40 and 41 in FIG. 7 which then function to penetrate the insulating material from each side as a result of heat and pressure supplied to each electrode; and when the corresponding electrode 40, 41 is in contact with the pin 130 and conductor 120, the pin and conductor are welded together.

The pins 120 prior to insertion may be tinned with solder and may in some cases, after being positioned as shown in FIG. 8, be soldered to the protruding end portion of the cable conductor.

The plastic insulating material may be, for example, Teflon in the various embodiments.

The connecting end pins in FIGS. 7 and 8 may be of various gauge, for example, of 20, 22 or 24 gauge and be

silver or gold plated nickel pins. The fusing of the various elements may be accomplished by welding or brazing or by soldering in one form of the invention described in FIG. 8 in some cases.

Usually, in making the end connections of FIGS. 7 and 8, the end connector is fused to the cable conductor at two spaced locations with two successive fusing operations using a single pair of electrodes or in a single operation using two pairs of electrodes.

While the particular embodiments of the present invention have been shown and described, it will be obvious to those skilled in the art that changes and modifications may be made without departing from this invention in its broader aspects and, therefore, the aim in the appended claims is to cover all such changes and modifications as fall within the true spirit and scope of this invention.

I claim:

1. Apparatus for making electrical connections to flexible ribbon-tape cables wherein conductors in the form of ribbons are embedded in a plastic material, a pair of pointed electrodes capable of applying pressure in a limited area to opposite sides of said tape cable, heating means mounted on each of said electrodes for softening the insulation of said tape cable when and as pressure is being applied to and between said electrodes.

2. In a method of making electrical connections between conductors of two flexible ribbon-type cables each of which comprise ribbon-type conductors embedded in a plastic insulating material, the steps comprising sandwiching said cables between a pair of heated electrodes, applying pressure between said electrodes to soften and crowd the plastic insulation out of that region between electrodes and adjacent conductors and between adjacent conductors, and applying a welding current through said elements after such heating and application of pressure results in a metal-to-metal contact between adjacent conductors and between adjacent electrodes.

3. In the method for making electrical connections between conductors of different ribbon-type cables wherein such conductors are embedded in a plastic insulating material, the steps comprising superimposing one of such cables on a second cable with the desired conductors to be connected in superimposed relationship, applying heat and pressure simultaneously between the insulating material which overlies such desired conductors to soften and crowd the insulating material away from such desired conductors, and thereafter passing a welding current through the superimposed conductors.

4. Apparatus for making electrical connections to an insulating body having conductors in the form of ribbons in said body, a pair of pointed electrodes capable of applying pressure in a limited area to opposite sides of said body, heating means on each of said electrodes for softening the insulation on said body when and as pressure is being applied to and between said electrodes.

5. In the method of making electrical connections between conductors of two insulating bodies each of which comprise ribbon-type conductors on a plastic insulating material, the steps comprising sandwiching said bodies between a pair of heated electrodes, applying pressure between said electrodes to soften and crowd the plastic insulation out of that region between electrodes and adjacent conductors and between adjacent conductors, and applying a welding current through said elements after said heating and application of pressure results in a metal-to-metal contact between adjacent conductors and adjacent electrodes.

6. In the method for making electrical connections between conductors of different insulated bodies wherein said conductors are on plastic insulating material, the steps comprising superimposing one of such bodies on a second body with the desired conductors to be connected in superimposed relationship, applying heat and pressure simultaneously between the insulating material which

overlies said conductors to soften and crowd the insulating material away from such conductors, and thereafter passing a welding current through the superimposed conductors.

7. Apparatus for making electrical connections to an insulating body having conductors in the form of ribbons in said body, a pair of electrodes capable of applying pressure in a limited area to opposite sides of said body, heating means mounted on each of said electrodes for softening the insulation on said body when and as pressure is applied to and between said electrodes.

8. Apparatus as set forth in claim 7 in which one of said electrodes has an arcuate grooved portion at its end for snugly engaging a wire which is to be connected to one of said conductors.

9. In a method for making electrical end connections to flexible ribbon-tape cables wherein conductors are embedded in a plastic material, the steps comprising inserting each of said end connections into one end of said cable in sandwiched relation between a corresponding one of said conductors and the plastic material overlying the same to crowd said overlying material away from the con-

ductor and stress the same with the said material maintaining said end connections against its corresponding conductor, applying heat and pressure to the plastic material on correspondingly opposite sides of said conductor and said end connection by a pair of heated electrodes to soften and crowd the plastic material out of that region between said electrodes and said end connection and said conductor, and thereafter passing a welding current through said electrodes to weld the end connection to a corresponding conductor.
